DESIGN FOR A HANDBAG

Zinaida Harpignies, Kew Gardens, N. Y.

Application September 30, 1943, Serial No. 111,241

Term of patent 7 years

To all whom it may concern:

Be it known that I, Zinaida Harpignies, a citizen of Belgium, residing at 84-09 Talbot Street, Kew Gardens, in the county of Queens and State of New York, have invented a new, original, and ornamental Design for a Handbag, of which the following is a specification, reference being had to the accompanying drawing, forming part thereof.

In the drawing

Fig. 1 is a front elevational view of a handbag showing my new design in closed position;

Fig. 2 is a front perspective view thereof in partly open position; and

Fig. 3 is a rear perspective view thereof in closed position with the handle broken away for convenience of illustration.

I claim:

The ornamental design for a handbag, as shown.

ZINAIDA HARPIGNIES.
